OTHER PUBLICATIONS

Notice of Allowance dated Apr. 18, 2016 from U.S. Appl. No. 29/527,085.

Office Action dated Feb. 1, 2016 from U.S. Appl. No. 29/516,707.

Primary Examiner — Rhea Shields(74) *Attorney, Agent, or Firm* — Ward and Smith, P.A.;
Ryan K. Simmons(57) **CLAIM**

The ornamental design for a closeable container, as shown and described.

DESCRIPTION

FIG. 1 is a perspective view of a closeable container showing a new design;

FIG. 2 is a front view thereof;

FIG. 3 is a rear view thereof;

FIG. 4 is a left side view thereof, the right side being a mirror image;

FIG. 5 is a top plan view thereof;

FIG. 6 is a bottom plan view thereof;

FIG. 7 is a perspective view of the closeable container of FIG. 1 in a partially opened configuration; and,

FIG. 8 is a plan view, showing the closeable container of FIG. 1 in a blank configuration.

In the drawings, the dash-dot-dash lines are for the purpose of illustrating perforations only and form a part of the claimed design.
